(57) CLAIM

The ornamental design for an electric air freshener, as shown and described.

DESCRIPTION

FIG. 1 is a rear perspective view of the body of the new air freshener design, shown separately for clarity of illustration.

FIG. 2 is a left side view of the FIG. 1.

FIG. 3 is a bottom view of the FIG. 1.

FIG. 4 is a right side view of the FIG. 1.

FIG. 5 is a front view of the FIG. 1.

FIG. 6 is a rear view of the FIG. 1.

FIG. 7 is a right side perspective view of the vessel of the new air freshener design, shown separately for clarity of illustration.

FIG. 8 is a top perspective view of the FIG. 7.

FIG. 9 is a rear perspective view of the electric air freshener.

FIG. 10 is a right side perspective view of the electric air freshener.

FIG. 11 is a right side view of the electric air freshener.

FIG. 12 is a left side view of the electric air freshener.

FIG. 13 is a rear view of the electric air freshener; and,

FIG. 14 is a front view of the electric air freshener.
